UNITED STATES PATENT OFFICE.

WILLIAM BUZBY TYLER, OF CAMDEN, NEW JERSEY.

COMBINATION GARMENT-SUSPENDER.

SPECIFICATION forming part of Letters Patent No. 750,325, dated January 26, 1904.

Application filed December 23, 1902. Serial No. 136,348. (No model.)

To all whom it may concern:

Be it known that I, WILLIAM BUZBY TYLER, a citizen of the United States, residing at Camden, in the county of Camden and State of New Jersey, have invented a new and useful Combination Garment-Suspender, of which the following is a specification.

The invention relates to a combination garment-suspender.

10 The object of the present invention is to improve the construction of garment-supporting devices and to provide a simple, inexpensive, and efficient one designed for the reception of garments of both men and women and 15 adapted to suspend a considerable number of the same, whereby a comparatively large number of garments may be properly cared for within a very small space.

20 A further object of the invention is to provide a garment-suspender of this character adapted to be supported by a rod, nail, hook, or similar fastening device and to enable the means for engaging such pole or fastening device to support the collar of a coat in proper 25 position.

With these and other objects in view the invention consists in the novel construction and arrangement of parts hereinafter fully described, illustrated in the accompanying drawings, and particularly pointed out in the claims 30 hereto appended, it being understood that changes in the form, proportion, and minor details of construction within the scope of the claims may be made without departing from 35 the spirit or sacrificing any of the advantages of the invention.

In the drawings, Figure 1 is a perspective view of a garment-suspending device constructed in accordance with this invention. 40 Fig. 2 is a rear elevation of the same. Fig. 3 is a transverse sectional view.

Like numerals of reference designate corresponding parts in all the figures of the drawings.

45 1 designates an oppositely-tapered bar forming the body portion of the garment-suspending device and having a curved upper edge to

conform to the configuration of a coat or similar garment, and extending from the ends of the bar 1 are coat-supporting loops 2, located 50 at the upper edge of the bar and substantially following the curvature of the same to form continuations thereof. The coat-supporting loops, which are preferably constructed of a single piece of stout wire or similar material, 55 are formed by coiling the wire to strengthen the outer portion of the loops and to provide the side portions thereof, and the terminals 3 of the wire are bent inward to form the inner transverse end portions of the coat-supporting loops and are provided with eyes for embracing the adjacent side of the loop.

The intermediate portion of the wire or other material of which the coat-supporting loops are constructed is extended longitudinally of 60 the bar or body portion of the garment-suspending device and is secured to the rear face of the same by means of staples 4, which receive the intermediate portion 5 of the wire near the ends of the bar or body portion. The 65 intermediate connecting portion of the wire is centrally extended to form a combined collar-supporting device and means for engaging a rod, hook, nail, or other fastening device. The wire is angularly bent to form two sides 70 75 6 and is secured by staples 7 or other suitable fastening devices arranged at the lower ends of the shanks of the hook-shaped sides 6. These hook-shaped sides form an upwardly-extending double hook and are connected at their outer depending portions or bills 8 by an inverted-U-shaped portion 9. The U-shaped connecting piece or portion 9 is located at the inner sides or faces of the bills of the double hook and reinforce the 80 same, which are connected at their upper ends by the top of the U-shaped connecting piece or portion, which prevents any separation of the sides of the double hook and which is arranged to engage a nail, hook, or similar fastening device for suspending the garment-supporting device. The double hook is also adapted to engage a horizontal pole or rod, which will extend longitudinally of the bar or 85 90

body portion and which will not interfere with the hanging of garments on the garment-suspending device. The double hook, which extends upward from the center of the bar or body portion, is arranged to support the collar of a coat for holding the same in proper position.

The bar or body portion 1 is provided at its opposite faces with garment-receiving hooks 10 and 11. The front hooks are arranged at the center and opposite side of the garment-supporting device, as clearly illustrated in Fig. 1 of the drawings, and the rear hooks are located at opposite sides of the center of the 15 rear face of the bar or body, as shown in Fig. 2; but the hooks may be arranged in any other desired manner, as will be readily understood. Each hook consists of a curved portion 12, centrally connected with an attachment-plate 13 and supported by a horizontal connecting portion 14, forming a brace and extending from the upper end of the curved portion to the attachment-plate. The curved portion 12, which is disposed in a vertical plane, curves 20 downward and outward from the attachment-plate and terminates in an upwardly-extending knob or enlargement. These hooks are adapted to receive skirts and other garments, and the bar or body portion 1 is also provided 25 at its upper edge with knobs 15, arranged at opposite sides of the center and adapted to receive and support shirts and other light garments. The knobs, which may be of any desired construction, are preferably provided 30 with threaded shanks, which are screwed into the bar or body portion 1, the latter being preferably constructed of wood.

The garment-suspending device is adapted for the reception of garments of both men and 40 women, and it is capable of receiving and properly arranging a comparatively large number of garments and of enabling the same to be arranged within a comparatively small space. The centrally-arranged upwardly-extending double hook is not only adapted to 45 permit the suspending device to be hung in a variety of ways, but it is also arranged to form a support for the collar of a coat or analogous garment for holding the same in proper position. Also the garment-supporting hooks 50 by being arranged at the front and rear faces of the bar or body portion are adapted when subjected to the weight of garments to prevent the same from twisting or canting the 55 device.

What is claimed is—

1. A garment-suspending device provided with means for holding garments, and having an upwardly-extending transversely-disposed 60 hook composed of two sides spaced apart and provided at the outer ends thereof with a connecting portion arranged to engage a fasten-

ing device, said hook being adapted to engage a pole or rod and to support the collar of a garment, substantially as described. 65

2. A garment-suspending device provided with means for holding garments, and having an upwardly-extending collar-supporting device consisting of a transversely-disposed hook adapted to engage a pole or rod and composed 70 of two sides spaced apart, and an inverted-U-shaped portion connecting the bills of the hooks and arranged to engage a fastening device, substantially as described.

3. A garment-suspending device comprising 75 a bar or body portion, coat-supporting loops, and a collar-supporting device formed integral with the loops, and consisting of a centrally-arranged upwardly-extending transversely-disposed double hook composed of two 80 sides spaced apart, and an inverted-U-shaped portion connecting the sides of the double hook at the bills thereof, substantially as described.

4. A garment-suspending device comprising 85 a bar forming a body portion and presenting flat vertical front and rear faces, means for suspending it from a support, and garment-receiving means projecting from each of the faces of the bar or body portion, substantially as described. 90

5. A garment-suspending device comprising 95 a bar forming a body portion presenting flat vertical front and rear faces, means arranged at the top thereof for suspending it from a support, and hooks extending from each of the faces of the bar or body portion and arranged to receive garments, substantially as described.

6. A garment-suspending device comprising 100 a bar forming a body portion presenting flat vertical front and rear faces, knobs projecting from the bar at the upper edges thereof, and a suspending device located between the knobs and arranged to support a collar, 105 substantially as described.

7. A garment-suspending device comprising 110 a bar forming a body portion presenting flat vertical front and rear faces, a central collar-supporting device consisting of a hook 115 for suspending the bar or body portion from a support, garment-receiving hooks projecting from each of the faces of the bar or body portion, and knobs arranged at the upper edge of the bar or body portion, substantially as described.

8. A garment-suspending device comprising 120 a bar or body portion, coat-supporting loops extending from the ends of the bar or body portion, a central collar-supporting device consisting of a transversely-disposed double hook composed of two sides spaced apart, and an inverted-U-shaped portion connecting the sides of the double hook at the

bills thereof and arranged to engage a fastening device, knobs arranged at the upper edge of the bar or body portion and located at opposite sides of the collar-supporting device, 5 and garment-receiving hooks extending from the opposite faces of the bar or body portion, substantially as described.

In testimony that I claim the foregoing as my own I have hereto affixed my signature in the presence of two witnesses.

WILLIAM BUZBY TYLER.
